H. C. STEPHENS ET AL

SAFETY HOOK

Filed July 18, 1923

UNITED STATES PATENT OFFICE.

HOMER C. STEPHENS AND HERBERT F. RANDOLPH, OF WEBB CITY, OKLAHOMA.

SAFETY HOOK.

Application filed July 18, 1923. Serial No. 652,435.

To all whom it may concern:

Be it known that we, HOMER C. STEPHENS and HERBERT F. RANDOLPH, citizens of the United States, residing at Webb City, in the county of Osage and State of Oklahoma, have invented certain new and useful Improvements in Safety Hooks, of which the following is a specification.

This invention relates to appliances used in the construction of oil wells and the primary object of the present invention is the provision of a novel safety device for holding the wire line in position to keep the same from going down the well during the spudding in of oil wells.

A further object of the invention is the provision of a novel safety hook or clamp for holding the wire line in position against displacement embodying a shank having means for connecting one end thereof to a suitable supporting post, and a resilient means for gripping the line wire, which is so constructed, that the tighter the pull on the wire, the tighter the clamp will be forced into engagement with the wire.

A further prime object of the invention is the provision of an improved safety wire grip of the above purpose embodying the shank for connection with a supporting post, a jaw rigidly formed on one end of the shank of arcuate formation, and a rockable jaw or arcuate formation disposed in superimposed relation to the rigid jaw and so arranged in relation thereto as to be forced closer into engagement with the rigid jaw, when tension is placed upon the wire line disposed between the jaws.

A still further object of the invention is to provide an improved safety hook for wire lines of well digging apparatus of the above character, which will be durable and efficient in use, one that will be simple and easy to manufacture and one which can be placed upon the market at a small cost.

With these and other objects in view, the invention consists in the novel construction, arrangement and formation of parts, as will be hereinafter more specifically described, claimed and illustrated in the accompanying drawings, in which drawings:

Figure 1 is a perspective view of the improved safety hook or wire clamp.

Figure 2 is a transverse section through the rigid and rockable jaws.

Figure 3 is a perspective view of the rockable jaw, and

Figure 4 is a perspective view of the bolt or pin upon which the rockable jaw is mounted.

Referring to the drawings in detail, wherein similar reference characters designate corresponding parts throughout the several views, the letter A generally indicates the improved tool or wire clamp, which embodies an elongated shank 5. The shank 65 5 has pivotally connected thereto at its outer end as at 6, a shackle or clevis 7, which permits the tool to be connected to a suitable supporting post or the like in spaced relation to the derrick floor. The inner end of 70 the shank 5 has integrally formed thereon the transversely extending rigid jaw 8, which is provided with an arcuate active wire engaging face 9. One end of the jaw 8 has formed thereon the forwardly extending 75 right angularly disposed supporting arm 10 which is provided at its outer end with the bearing 11 for receiving the supporting pin or bolt 12 for the rockable jaw 15.

The rigid jaw 8 and the arm 10 are preferably braced by integral ribs 13, which extend from the shank 5 longitudinally across the jaw 8 and arm 10. The supporting pin or bolt 12 is of a cylindrical form and has one end provided with a polygonal head 14 80 and its opposite end provided with a reduced threaded extension 16, for a nut 17 which is adapted to be threaded on said extension 16 for firmly holding the bolt or pin in position on the arm 10. 90

The jaw 15 is rockably mounted upon the cylindrical portion of the bolt or pin 12 and embodies the arcuate body portion 18 for forming the transverse arcuate jaw face 19, which is disposed in superimposed relation to the arcuate jaw face 9. The opposite terminals of the jaw body 18 supports parallel disposed pivot ears 20 which are provided with longitudinally aligned openings 21 for receiving the supporting bolt 100 or pin 12. By this construction it can be seen that the jaw 15 is free to rock upon the bolt. 95

In order to normally maintain the jaw 15 swung away from the jaw 9 and thus allow 105 the ready insertion of the line wire between the jaw an expansion spring 22 is coiled about the bolt 12. This expansion spring 22 has one terminal thereof secured to the bolt as at 23 and its opposite terminals secured to the jaw 15 as at 24. The non-active face of the jaw 15 can be cut away 110

as at 25 in order to permit the expansion and contraction of the said spring.

The jaws 8 and 9 at their ends remote from the arm 10 can be provided with lugs 5 26 and 27 respectively, which serve as means for limiting the inward swinging movement of the jaw 15 and also provide means for preventing the slipping of the line wire from out of engagement with the said jaws.

10 From the foregoing description, it can be seen that an improved line wire gripping device has been provided, in which the line wire can be readily and quickly inserted between the jaws, without necessitating the threading of the line wire therebetween, and which is also so constructed as to permit the jaw 15 to be moved in closer relation with the jaw 8 as greater tension is placed upon the line wire, thereby insuring a tight grip being had upon the line wire to prevent the slipping thereof.

Changes in details may be made without departing from the spirit or the scope of this invention.

25 What we claim as new is:

1. A line wire gripping tool comprising a shank, a laterally extending rigid jaw projecting from one end of the shank and a movable jaw associated with the shank and disposed in spaced parallel relation to the first mentioned jaw.

2. In a line wire gripping tool, a longitudinally extending shank, a clevis pivoted to the outer end of the shank, a transversely extending rigid jaw projecting laterally from the inner end of the shank, a rockable jaw associated with the shank and disposed in spaced relation to the rigid jaw, and oppositely directed active jaw faces formed on said jaws.

3. In a line wire gripping tool, an elongated shank, a clevis pivotally secured to the outer end of the shank, and a transversely extending rigid jaw formed on the inner end of the shank, a forwardly extending rigid

arm formed on one end of the rigid jaw, a supporting bolt connected with the arm and arranged in spaced parallel relation to the rigid jaw, and a rockable jaw mounted upon said bolt, the jaws having their active jaw 50 faces arcuate-shaped in cross section.

4. In a line wire gripping tool, an elongated shank, a pivoted clevis carried by one end of the shank, a transversely extending rigid jaw formed on the forward end of the shank, a rigid supporting arm formed on one end of the jaw, a bolt detachably connected with the arm and arranged in spaced parallel relation to the jaw, a movable jaw rockably mounted upon the bolt including an 55 active jaw face and pivot ears for receiving the bolt, and resilient means for normally holding the movable jaw in a predetermined position away from the rigid jaw.

5. In a line wire gripping tool, an elongated shank, a pivoted shackle secured to the outer end of the shank, a rigid jaw formed on the inner end of the shank, a forwardly extending arm formed on one end of the jaw, a pivot bolt detachably secured with 60 the arm arranged in spaced parallel relation to the rigid jaw, a movable jaw rockably mounted upon the bolt including an arcuate jaw face and a pair of pivot ears for receiving the bolt, an expansion spring 65 coiled about the bolt having its terminals connected respectively to the bolt and movable jaw for holding the movable jaw in a predetermined position in relation to the rigid jaw, the jaws being provided with 70 oppositely directed arcuate jaw faces, and limiting stop lugs formed on the meeting faces of said jaws.

In testimony whereof we affix our signatures in presence of two witnesses.

HOMER C. STEPHENS.
HERBERT F. RANDOLPH.
